United States Patent Office

Des. 180,552
Patented July 2, 1957

180,552

PAPER NAPKIN

William S. Huss, Appleton, Wis., and John E. Lynch, Mount Prospect, Ill., assignors to Marathon Corporation, Menasha, Wis., a corporation of Wisconsin

Application August 13, 1956, Serial No. 42,586

Term of patent 14 years

(Cl. D59—2)

The figure is a plan view of a half section of a paper napkin showing our new design, the lower half section being substantially the same and arranged in proper relation to complete the napkin.

We claim:

The ornamental design for a paper napkin, substantially as shown and described.
